V. A. FISCHER

CHAIN REPAIR TOOL

Filed April 10, 1924

Inventor
Victor A. Fischer
Attorney.

UNITED STATES PATENT OFFICE.

VICTOR A. FISCHER, OF NEW YORK, N. Y.

CHAIN-REPAIR TOOL.

Application filed April 10, 1924. Serial No. 705,563.

To all whom it may concern:

Be it known that I, VICTOR A. FISCHER, a citizen of the United States, and resident of New York city, county of New York, and 5 State of New York, have invented an Improvement in Chain-Repair Tools, of which the following is a specification.

My invention has for an object the provision of a portable tool, especially adapted 10 for use as part of the equipment of the tool chest of an automobile or garage, for use more especially in repairing "Weed" chains or their equivalent, wherein the worn transverse chain link-bars must, when worn, 15 be removed and replaced by new ones.

More generically considered, my invention is adapted for opening and closing chain link loops, irrespective of the use of the chain.

20 With the above and other objects in view, the nature of which will be more fully understood from the description herein-after, the invention consists in the novel construction of chain repair tool, as herein-25 after more fully described and defined in the claims.

Referring to the drawings: Fig. 1 is a side elevation of my improved chain repairing tool in the act of fully opening a 30 loop of a chain link; Fig. 2 is a similar view of the operative parts in the initial act of opening the loops of a chain link; Fig. 3 is a similar view but showing the operative parts in the final act of closing 35 the loops of a chain link; Fig. 4 is a plan view of the same; Fig. 5 is a front view of the same; and Fig. 6 is a perspective view of the opening wedge blade.

2 is the body of the upper jaw 3 and said 40 body is provided with clamping means comprising a fixed jaw 4 and clamping screw 5 having the handle part 6. This clamping means allows of the tool being conveniently clamped upon the running board of the 45 automobile. The jaw 3 is curved and providing a wide curved clamping surface 10, preferably having a central rib 18 (Fig. 5). 9 is a lever hinged to the side of the body 2 at 8 by a transverse pivot-bolt, and having the 50 short arm formed as a curved jaw 7 arranged immediately below and oppositely directed to the jaw 3; said jaw 7 likewise having the wide curved clamping surface 11, preferably providing a central rib 19. 55 The ribs 18 and 19 are in the same vertical alinement, but, if desired, these ribs may be omitted. 24 is a spring for normally opening the jaws 3 and 7, as shown in Fig. 2. To the end of the jaw 7 is hinged a wedge shaped blade 12 having a broad base at 16 60 to abut the flattened end 14 of the jaw and also having the hinge lug 15 which fits into a slotted provision in the end of the jaw and joined thereto by the transverse hinge pin 13. This lower jaw 7 may also 65 be provided at its end nearest to the hinge or fulcrum point 8 with a downwardly extending slot 17 for receiving the chain link 23, as shown.

The operation and functioning of the 70 tool in repairing a "Weed" chain will now be understood. Assuming that a worn transverse link 20 is to be disconnected from a longitudinal link element 23, the latter is set in the slot 17, the two loops 21 of the 75 link 20 seated respectively on the curved surfaces 10 and on opposite sides of the rib 18. The wedge blade 12 is then turned upward to enter between the ends 22 of the loops and the link body portions 20, as indicated in Fig. 2. The lever arm 9 is then depressed with the result that the looped ends 21 are opened up widely by the action of the wedge blade 12, it swinging inwardly 80 as the jaw 7 rises toward jaw 3, as indicated 85 in Fig. 1. In closing the open link loops 21, whether of the same link or of another link in open condition, the link loop is placed between the open jaws 3 and 7, but in an inverted position to what is shown in Fig. 90 2 and after the wedge blade 12 has been turned outward, as in Fig. 3; and thereupon the lever arm 9 is depressed, with the result that the looped ends 21 of the link are closed, as clearly shown in Fig. 3. In this way, the 95 link 20 is securely attached to one bar of the longitudinal link 23. During these operations, the longitudinal links of the "Weed" chain structure are free to move in the slot 17 when opening or closing the link loop 21, 100 as will be readily understood by comparing Figs. 1, 2 and 3. As the link 20, as ordinarily constructed, is provided with two parallel link loops 21 (Figs. 4 and 5), they 105 are maintained with a slight separation during the act of opening and closing by the presence of the ribs 18 and 19 (Fig. 5). Furthermore, these ribs centralize the loops between the jaws 3 and 7, thereby insuring 110 them being properly operated upon during

the manipulation of the tool. The ribs prevent lateral slipping or displacement of the loops within the jaws.

It will further be understood that the 5 opening wedge blade 12 is free to swing on its pivot 13 when opening the link 21, as will be apparent by noting the different positions assumed in Figs. 1 and 2. In closing the links, however, this wedge blade 12 10 is turned in the outward position, as shown in Fig. 3, and thereby constitutes an extension to the jaw 7 which supports the link 20 in a positive manner when the tool is being operated in the act of closing the links.

15 It will now be apparent that I have devised a novel and useful construction which embodies the features of advantage enumerated as desirable, and while I have in the present instance shown and described the 20 preferred embodiment thereof which has been found in practice to give satisfactory and reliable results, it is to be understood that I do not restrict myself to the details, as the same are susceptible of modification 25 in various particulars without departing from the spirit or scope of the invention.

Having now described my invention, what I claim as new and desire to secure by Letters Patent is:

30 1. In a tool for opening and closing chain links, the combination of two jaws hinged together and provided with means for imparting a relative opening and closing motion thereto, said jaws having their opposing faces shaped to receive and grasp a 35 looped end of a chain link, one of said jaws being provided with an adjustable wedge shaped blade and of such proportions that the wedge end thereof may be directed in-

ward between the jaws as when opening the 40 link and directed outward away from the jaws when closing the link.

2. The invention according to claim 1, when further distinguished by having the wedge shaped blade hinged to the outer end 45 of one of the jaws in such manner that when the wedge end is turned outward away from the jaws, it is positively held as an extension to the jaw and forms a support for the body of the link to prevent it shifting 50 during the closing operation.

3. The invention according to claim 1, wherein further, one of the jaws is provided with a transverse slot opening tangentially to the hinge and from the inner operating surface of the jaw for receiving one of the longitudinal chain links and permitting it to rise and fall in the slot during the operation upon the looped portions of the other or transverse links.

4. The invention according to claim 1, wherein further, the opposing surfaces of the two jaws are oppositely curved and each is provided with a wide transverse surface 60 having a centrally projecting rib.

5. The invention according to claim 1, wherein the wedge shaped blade is directly hinged in an adjustable manner and is provided with an extended base at the hinged end which abuts the end of the jaw when turned in an extended position away from the hinge, whereby it is supported in such manner as to act as a guide and sustain the body of the link when the looped end thereof is being closed.

In testimony of which invention, I hereunto set my hand:

VICTOR A. FISCHER.
